UNITED STATES PATENT OFFICE.

WILLIAM GEISER, OF SALINA, PENNSYLVANIA.

DEVICE FOR EJECTING OIL FROM OIL-WELLS.

SPECIFICATION forming part of Letters Patent No. 404,397, dated June 4, 1889.

Application filed November 1, 1888. Serial No. 289,709. (No model.)

To all whom it may concern:

Be it known that I, WILLIAM GEISER, a citizen of the United States, residing at Salina, in the county of Venango and State of Pennsylvania, have invented a new and useful Device for Ejecting the Oil out of Oil-Well, of which the following is a specification.

My invention relates to improvements in devices for ejecting the oil out of oil-wells by means of a gas-jet, and the objects of my improvements are, first, to prevent any escape from the well of gas produced above the oil-rock; second, to protect the oil-producing rock from the pressure of the confined gas, and, third, to protect the oil-producing rock from any pressure of gas or oil within the oil-tubing, but leave at all times a free exit for gas produced in the oil-rock. I attain these objects, as shown in the accompanying drawings, in which—

Figure 1, Sheet 1, shows the device complete, being in part elevation and part a vertical section. Figs. 2, 3, and 4, Sheet 2, show in detail the construction of the casing-head to prevent the escape of gas from the well except by way of the oil-tubing. Figs. 5, 6, 7, and 8 show in detail the construction of the packer to protect the oil-producing rock from the pressure of the confined gas. Fig. 9 is a vertical section of a valve-cage inclosing a valve to protect the oil-producing rock from any pressure within the tubing. Fig. 10 is a vertical section of a so-called "ejector." Fig. 11 is a top view of the ejector. Fig. 12, Sheet 3, is a modification of the device shown in Fig. 1, Sheet 1.

Similar letters refer to similar parts throughout the several views.

The tubing A A' A², with the T D, is the same as commonly used in oil-wells, through which the oil flows or is pumped to the surface. The section A extends from the oil-rock upward, and is connected at its upper end by a coupling to the ejector B. To the upper end of ejector B is connected by a coupling a like tube A', having its upper end connected by a reducer to the sleeve C, which carries the packer C'. Projecting through the packer C' into the metal sleeve C is a third tube A², which continues upward and out at the top of the well, where it is connected by

the pipe A³ with a receptacle for the oil. This furnishes a continuous passage for the oil, unobstructed except by the valve h, which opens upward, and therefore does not prevent the passage of oil. The T D is placed in the tube A to admit the oil, the lower end of the said tube being closed by resting upon the bottom of the well.

The metal pipe E (called "casing") is put into the well and extends down, as usual, to a point below salt-water, but terminates above the gas-producing rock.

E' is the body of the casing-head, having a recess e to receive the projection e' on the cover E². Between these surfaces is placed some compressible material, and the cover is then bolted to the body of the casing-head by the bolts e². Placing the packing material in a recess, as shown, is preferable, as it prevents any possibility of its being blown out if exposed to a very high pressure. Through the cover E² is a hole e³ for the tube A² to pass through, and also a smaller hole e⁴ for the pipe F to pass through. These holes for a short distance from the inside of the cover are just large enough to pass the said tube and pipe through easily, beyond which they are enlarged, forming chambers for material to pack around said tube and pipe. The material is compressed in the chambers by the glands or followers e⁵ e⁶, which are drawn into the chambers by turning the nuts e⁶ e⁷ on their studs. The whole forms two stuffing-boxes of common construction, and will effectually prevent the escape of any gas through the casing-head along the tube and pipe.

The packer C' is placed below the gas-producing rock, between it and the oil-producing rock. It may be made of rubber or any suitable material, and is supported upon the flange c of the metal sleeve C. This flange is circular and is eccentric to the sleeve C, and has a hole c' for the pipe F to pass through, and has also the packer C' and the metal plate c², a top view of which is shown in Fig. 8.

In lowering the tubing A A' A² into the well the packer is carried on the coupling a, which is screwed onto the end of the tube A² and passes down with the tubing until it is brought to rest by the tube A coming into

contact with the bottom of the well; but the tube A^2 still continues to pass down until the coupling a' rests upon the metal plate c^2 and the packer C' has been sufficiently compressed 5 to support the weight of the tube A^2 . The weight of the tube A^2 is great enough to compress the packer C' longitudinally and cause it to spread until it entirely fills the space in the well around the tube A^2 and pipe F . This 10 confines the gas to the space above the packer and protects the oil-rock from the pressure of the accumulated gas.

f is an opening in the side of the casing-head through which the gas is conveyed from 15 inside the casing through the pipes $F' F^2 F^3$ to the pipe F , thence down into the ejector B , from which it escapes upward through the small hole g into the tube A' above the check-valve h . The current of gas as it passes up 20 the tubing expels the air, creating a partial vacuum, which will be immediately filled by the oil from below until it rises above the ejector B and comes in contact with the escaping gas, which will carry it along up the 25 tubing through the pipe A^3 into the receptacle provided for it. This operation may continue until the accumulation of oil is exhausted or the gas-pressure too much reduced. Then the valve G is closed to prevent further 30 escape of the gas until the gage H indicates the required pressure, when the operation may be repeated.

Should the accumulation of oil be too slow and the gage H show a dangerous pressure, 35 the valve G may be opened until the surplus escapes as it accumulates into the tubing $A A' A^2$; or a pipe I may be screwed into the casing-head, through which it may be conveyed into the casing of another well provided with 40 this device, there to be used to blow out the oil, as in this.

Fig. 9 is a vertical section of a cage inclosing a valve h . This cage is provided with a thread h' below the openings i , which screws

into the thread g' in the lower end of the 45 ejector B . Any pressure of gas or oil from the oil-producing rock will raise the valve h from its seat and escape through the openings i into the ejector B , thence up the tubing $A A' A^2$, while any pressure from above will be 50 prevented from passing down into the oil-rock.

J is a check-valve to prevent a flow of oil through pipes $F^3 F^2 F'$ into the casing E should the oil rise in the tubing $A A' A^2$ to a higher level. 55

In case of a well which produces no gas above the oil-rock a supply of gas may be brought from some other source through the pipe F^4 , in which case the pipes $F^2 F'$ would be dispensed with, and the packer C' , also the 60 tight casing-head, would also be unnecessary. This modification of the device is shown in Fig. 12, Sheet 3; but in case of a well producing a small quantity of gas above the oil-rock, but not in sufficient quantity, the pipes $F^2 F'$ 65 would still be necessary, and when using gas from the casing E the valve G^2 should be closed, and when using gas from pipe F^4 the valve G' should be closed.

I am aware that prior to my invention gas 70 has been conveyed down into oil-wells through a pipe and allowed to escape upward to blow out the oil. I therefore do not claim such a device, broadly; but

What I do claim as my invention, and desire to secure by Letters Patent, is— 75

1. The combination, substantially as set forth, of the oil-tubing $A A' A^2$ with the pipe F , located outside of the oil-tubing, the ejector B , and check-valve J . 80
2. The combination, substantially as set forth, of a pipe F , check-valve J , ejector B , check-valve h , oil-tubing $A A' A^2$, packer $C' C^2$, and casing-head $E' E^2$.

WILLIAM GEISER.
